BIRD FEEDING STATION

Norvel H. Jones, Miami, Fla.

Application December 1, 1958, Serial No. 53,592

Term of patent 14 years

(Cl. D31—2)

Figure 1 is an elevational view of a bird feeding station embodying my new design;

Figure 2 is a top plan view thereof; and

Figure 3 is a sectional view taken on line 3—3 of Figure 2.

I claim:

The ornamental design for a bird feeding station, as shown.
